UNITED STATES PATENT OFFICE.

THEODORE K. HASTINGS, OF BROOKLYN, NEW YORK, ASSIGNOR TO
HASTINGS AND MILLER, OF NEW YORK, N. Y., A FIRM.

PASSE-PARTOUT.

SPECIFICATION forming part of Letters Patent No. 691,544, dated January 21, 1902.

Application filed August 24, 1901. Serial No. 73,119. (No model.)

To all whom it may concern:

Be it known that I, THEODORE K. HASTINGS, a citizen of the United States, residing in the borough of Brooklyn, county of Kings, city 5 and State of New York, have invented an Improvement in Passe-Partouts, of which the following is a specification.

A passe-partout as usually constructed is a picture and mat framed with a glass and edge-binding complete in itself as the most inexpensive article of this class for sale and decoration, and the same is not adapted to be altered or separated.

My invention is a new article of manufacture, and in carrying out the same the passe-partout is prepared as an article of sale complete and ready to receive a picture placed upon a filling-board provided for that purpose, after which a sheet of paper attached 20 along one edge is to be pasted down to complete the frame or passe-partout.

In the drawings, Figure 1 is a rear perspective view illustrating my invention, and Fig. 2 is a vertical section in larger size.

25 The glass *a* and mat *b* agree in size and may be of any desired surface dimensions. The mat is provided with a picture-opening, which may also be of any desired dimensions proportionate with the mat and glass. The backing-card *d* also agrees in size with the mat and glass, and the same is preferably pasted down upon the back of the mat. This backing-card is provided with an opening larger than the opening in the mat, and into which the card 30 *c*; preferably of the same thickness, fits. In fact, this card *c* may be cut directly from the backing-card *d*.

35 The picture to be shown in the passe-partout is preferably pasted upon one surface of the card *c*. The glass *a*, mat *b*, and backing-card *d* are connected by a binding *e*, extending entirely around the edges of the respective parts, said binding extending a short distance over the surface of the glass and over 40 the surface of the backing-card *d*.

45 I employ a paper sheet *f*, pasted along one edge upon the binding and the backing-card. The loose edges of this paper sheet on the under surface are preferably provided with 50 adhesive material at *f'*, as shown by the parallel lines. As an article of manufacture and for sale the device is provided, as described,

with the card *c* for the picture, fitting and loose within the opening of the backing-card *d*, and the paper strip *f*, simply secured along 55 one edge, as shown in Fig. 1. The person purchasing the same for use and for exhibiting a picture preferably pastes the picture on one face of the filling-card *c*, lays the card in the opening in the backing-card *d*, so that the 60 picture will show in the opening in the mat, and then moistens the adhesive material upon the under surface of the paper backing-sheet *f* or applies paste to the edges and pastes the same down upon the backing-card *d* and binding-strip *e*, so as to inclose and hold the picture and the card *c* in place in the passe-partout.

I may attach to the back of the passe-partout one or more rings *g*, by which the same 70 may be suspended from a nail or picture-wire upon the wall.

I claim as my invention—

1. As a new article of manufacture, a passe-partout comprising a glass, a mat with a picture-opening, a backing-card with an opening 75 larger than the opening in the mat, an edge-binding connecting said parts together, a card adapted to fit within the opening in the backing-card and upon which the picture 80 to be exhibited may be pasted, and a paper sheet secured along one edge to the backing-card and adapted to be pasted down upon the backing-card after the insertion of the picture, substantially as set forth. 85

2. As a new article of manufacture, a passe-partout comprising a glass, a mat with a picture-opening, a backing-card with an opening larger than the opening in the mat, an edge-binding connecting said parts together, 90 a card adapted to fit within the opening in the backing-card and upon which the picture to be exhibited may be pasted, and a paper backing-sheet secured along one edge to the backing-card and having adhesive material 95 upon its free under edges and adapted to be pasted down upon the backing-card after the insertion of the picture, substantially as set forth.

Signed by me this 19th day of August, 1901. 100
THEODORE K. HASTINGS.
